COIN SLIDE

Herbert G. Breitenstein, Chicago, Ill., assignor to
Raymond T. Moloney, Chicago, Ill.

Application September 7, 1933, Serial No. 688,428

6 Claims. (Cl. 194—101)

This invention relates to coin slides used in connection with coin released games or vending machines.

The primary object of the invention is to provide a simple, inexpensive, foolproof coin slide which will release the associated coin controlled game, vending machine, or other mechanism, only when an authorized coin is handled by the coin slide. If an unauthorized coin is used the slide 10 will not release the associated mechanism and the unauthorized coin will be ejected inside the box containing the coin released mechanism where the slug or the like is removed from circulation and possible further attempts to use the 15 same.

The general object of the invention is to prevent the slide from releasing the associated mechanism when coins not having the required characteristics of value, thickness, diameter, and 20 composition, such as requisite metal, are attempted to be passed through the slide. Also it is intended to prevent use of coins having an aperture, as certain perforated or apertured foreign coins.

Briefly, the coin slide is conventionally mounted horizontally in the wall of a game or the like, said slide being accessible outside the game box to receive a coin in a coin pocket provided therein for that purpose, while the foolproof coin handling mechanism of the slide is inside the game 30 box inaccessible to the player. The slide is slidably supported in a stationary guide to cause the slide to move along a straight line. If the coin is of the proper size it can be slid into the game box by the slide and providing it is non-magnetic such as our standard five cent piece, 35 which we will here consider to be the authorized coin, the slide can then be pushed home to its innermost position to effect release of the coin controlled mechanism. It is to be understood 40 that the associated mechanism can only be released or unlocked when the slide has been moved substantially the full distance of its stroke into the cabinet or box containing the mechanism to be released. Should the coin be magnetic, a mag-

net picks it up at an initial point of movement inward of the slide so that no coin is lodged in the coin pocket when inward movement of the slide is continued. When the empty pocket reaches a certain point in its inward travel, a pair 50 of spring pressed sliding plungers enter the pocket to lock the slide against further movement. When the operator releases his hand from the slide a spring pulls the slide back to its starting position and on the way mechanism is operative 55 to free the coin from the magnet and flip it to one

side where it falls into the cabinet and is not returned to the player. If no coin is used a single spring pressed plunger is immediately operative after slight movement of the slide to engage the empty coin pocket and lock the slide against further inward movement. If a cardboard disk is employed, this same plunger would bite into the disk and stop the slide. Should an apertured coin be used, this same plunger would be forced into the hole in the coin to stop the slide. Such coin, 10 however, would be withdrawn with the slide because of its lodgement in the pocket where the player could get it back. 5

So much will suffice to give a general understanding of the purposes and structure of the 15 slide. The invention is illustrated in detail in the accompanying sheets of drawings wherein:

Figure 1 is a top plan view of the improved coin slide;

Figure 2 is a side elevational view of the slide; 20

Figure 3 is a bottom plan view of the slide;

Figure 4 is a transverse, cross sectional view 25 through the slide as seen in the direction of the arrows along the line 4—4 of Figure 2 and showing in particular the pin and cam means for ejecting an unauthorized magnetic coin from the slide;

Figure 5 is a similar cross sectional view 30 through the slide as seen along the line 5—5 of Figure 1, looking in the indicated direction, and particularly showing the two spring pressed plungers for locking in the empty coin pocket of the slide to prevent its full inward movement;

Figure 6 is a longitudinal side section through 35 the entire slide as seen along the line 6—6 appearing in Figure 1 looking in the direction of the arrows;

Figure 7 is a cross sectional view through the slide at the line 7—7 of Figure 2, looking in the indicated direction, to show the single, forward 40 spring pressed plunger; and

Figure 8 is a fragmentary plan view of the slide showing a modified form of mechanism for laterally ejecting a magnetic coin.

For the sake of clearness, the cabinet or box 45 of a game or vending machine, to which the slide is attached, has not been shown; also the mechanism to be released by the slide and its connection with the slide likewise have not been shown, as these things form no part of the invention, and 50 in any event they are well understood in this art and therefore unnecessary to a complete understanding of the invention.

In the drawings, as shown, the slide comprises 55 a plate 10 having a screw tapped boss 11 for se-

curement in the desired way to a wall of the cabinet, said plate having formed therewith a horizontal guide 12 extending in front of, as well as in back of, the plate 10, it being understood that 5 the portion of the guide rearward of the plate is inserted through a suitable slot in the cabinet wall closed by the plate. Thus the major portion of the guide and all of the foolproof mechanism carried thereby, presently to be described, are 10 located within the cabinet inaccessible to the operator. The guide 12 is thus stationary and rigidly mounted.

This guide 12 presents a flat horizontal surface as shown in Figures 1 and 3 formed outside 15 or forwardly of the plate 10 with a small finger hole 13 and at an inner intermediate point with a larger coin drop hole 14. Outside the plate 10 the guide is depressed along its longitudinal median line as shown in Figures 3 and 6 to provide a longitudinal guide groove 15 which is continued as shown behind the finger hole 13 into the plate part of the structure. The rear, or inner end, of the guide, in which the coin drop hole 14 is formed is depressed and at its rear or inner end 20 carries on its top surface a stop block 16 securely held in place by a screw bolt 17 or other suitable means. A spacer 18 is laid on the guide surface as shown in Figure 6 between its channeled edges, said spacer plate being held in place by four 25 screws 19 as appears in the bottom view in Figure 3. This spacer plate 18 is stationary and formed with a coin drop hole 20 in registration with the hole 14 heretofore described. The midportion of the guide frame just back of the plate 30 10 is open at 21 to save metal, such opening being relatively narrow so that a coin can be passed thereacross, by the hand pushed slide next to be described.

This slide is an elongated flat strip 22 resting 40 slidably and horizontally on the guide surface and between its channeled edges, said slide 22 having a bent handle end 23 for ease of manipulation. This slide is longer than the guide and passes inwardly through the plate 10, over the spacer plate 45 18 on which it slides, and back to a point beyond the inner end of the guide frame. At its rear end the slide carries at its bottom a pin 24 to which is connected one end of a spring 25, said spring having its other end anchored to a pin 26 carried by the under side of the guide frame 12 adjacent the opening 21 as shown in Figure 3. It 50 will be understood after the slide is pushed inwardly the spring serves to return the slide to normal starting position when released by the operator's hand.

At its forward end the slide 22 has a coin receiving pocket or opening 27 of the proper size, said opening 27 normally, or in the starting position of the slide being directly over the finger 60 hole 13 in the guide. Further, the coin hole 27 is larger than the finger hole 13 so that the coin will be supported in the pocket by the guide and cannot fall through. Forwardly of the coin pocket opening 27 the slide has a central, longitudinally disposed short depression to form a nib or boss 28 that fits down and slides in the groove 15 to guide the slide in its longitudinal sliding movements. Just to the rear of the hole 27 the slide carries a downwardly extending guide block 70 or pin 29 moving through the guide groove 15 formed in line with the plate 10 as shown in Figure 6. Just rearwardly of the pin 29 the slide carries an upstanding pin 30 for a purpose later to appear.

75 Looking at Figures 2 and 7 it will be seen that

a cross plate 31 is fastened to the side of the guide frame 12 while on its opposite side the guide frame has fastened thereto an upstanding block 32 interfitted with the cross plate 31 to hold the same securely in place, said plate or bar 31 being spaced above the slide 22 to permit the same to slide freely between said plate 31 and guide 12 as will be understood. Along its longitudinal median line the underside of the plate 31 is formed with a groove 33 in which the pin 30 moves. In 10 a vertical bore 34 formed in the bar 31 between its ends, is a centrally disposed plunger 35 having a lower beveled edge 36, said plunger being pressed downwardly by a flat spring 37 carried by the block 32, as shown.

15 Between the lightener hole 21 and the coin drop hole 14 the underside of the guide frame 12 carries a second cross bar or plate 38 as shown in Figures 3 and 5, said plate 38 being securely fastened at its ends to the edges of the guide frame. A block 39 is secured to this plate midway between its ends, said block having secured thereto, as shown, a transverse flat spring having curled ends 40 engaging and pressing upwardly a pair of plungers 41 similar to the plunger 35 25 heretofore described. These plungers 41 each pass up through bores formed in the guide 12 as shown in Figure 5 and are spaced so that when the empty coin hole 27 is in line both plungers are pressed into the empty hole and engage the 30 same at transversely diametric opposite points, while the first plunger 35 engages said empty hole along the longitudinal diametric line of the hole.

As shown best in Figures 1 and 5 the top edges 35 of the guide frame 12, above the plate 38 carry a plate 42, fastened to the frame by screws, said plate, as shown providing shoulders 43 at each edge between which is arranged, flatly, a magnet 44 held down by a clamp device 45. The legs 40 of the horseshoe magnet extend forwardly toward the plate 10 a substantial distance beyond the front edge of the plate 42 and above the open guide frame and the slide 22 so that in the event a magnetic coin is advanced by the slide to this 45 point, the magnet legs are instantly operative to pick up and catch such coin. Centrally and longitudinally the under side of the plate 42 is formed with a groove 46 through which the central pin 30 on the top side of the slide guides 50 and passes when the slide is moved that far.

The longitudinal central portion of the slide 22 from the pin 30 back to a point near its rear end is formed with a slot 47 the end of which in the starting position stops against the block 16, said slot guiding along the sides of said block as shown in Figure 1. Thus the block 16 serves to limit the forward sliding of the slide under the influence of the spring 25.

It will be remembered as an object of the 60 invention that it was desired to eject magnetic coins and slugs laterally out of the slide and into the cabinet where the operator could not retrieve his coin. Accordingly, the rear edge of the cross plate 31 is formed as a wedging cam 65 edge or surface 48. The pin 30 heretofore described is behind a magnetic coin or slug held by the magnet and as the spring 25 returns the slide forwardly to its starting position the pin 30 pushes the coin forwardly to release it from the magnet and force it against this cam edge 48 and because of its receding curvature, and the fact that the coin is circular, the coin is ejected laterally out of the slide. In the event 70 that the central pin 30 fails to accomplish this 75

function alone, a second offset pin 49 is mounted on the slide. Said pin 49 is offset from the pin 30 in the direction of movement followed by the ejecting coin, and further said pin is somewhat rearwardly disposed on the slide relative to the pin 30. See Figures 1, 2 and 4. A passage 50 is formed longitudinally through the under side of the plate 43 to accommodate the pin 49 as the slide is moved. The operation and use 10 of the slide under varying conditions will now be described.

First we will assume an authentic coin, such as the five cent piece is employed. The coin is placed in the pocket 27 and thereupon the operator 15 grasps the handle 23 and pushes the slide inwardly against the force of the spring 25. As the pocket 27 with the coin therein presents a flat surface it rides under the yielding front plunger 35 which is thus made inoperative by 20 the presence of the coin. Similarly as the slide advances the pocket and coin, the latter passes by the magnet and the two rear plungers 41 which cannot function to stop the slide when a coin is in the pocket. As the coin moves along 25 it finally reaches a position directly over the registering coin drop openings 20 in the spacer 18 and 14 in the guide frame. Thus the coin drops through, free of the slide, and as the slide has now advanced the full stroke, the associated 30 game or vending mechanism is released or unlocked. The user now releases his hand from the slide and the spring 25 is operative to return the slide to its initial starting position.

Should an attempt be made to pass a magnetic 35 coin or slug, the magnet 44 is strong enough instantly to pick up the coin as it moves out from under the plate 31 and raise it to a position above the slide so that the slide continues inwardly with an empty pocket 27. When the empty 40 pocket passes over the two plungers 41 they are spring pressed into the empty hole 27 to lock the slide against further inward movement. Thus under such conditions the slide cannot be advanced a full stroke to release the coin controlled, 45 associated mechanism. Again, when the operator releases the slide, the spring 25 pulls it back and the spring pressed plungers 41, which have wedge-shaped lower ends, merely ride out of the hole 27 in a manner that will be readily understood. The supplemental pin 49 assists in 50 ejecting the coin.

If it is attempted to move the slide in without any coin in the pocket 27 then the front plunger 35 is immediately pressed into the empty hole 55 27 to lock the slide.

If a cardboard disk is played, then the front plunger 35 again immediately is pressed into and scores or perforates the disk to lock the slide against further movement.

If a coin having a central aperture is played 60 then again the front plunger 35 is forced thereinto to lock the slide against further movement. Such coin can only be moved as far as the plunger 35 and when the spring 25 pulls the 65 slide back, such coin is returned to the player because it is pocketed in the hole 27 and must move back with the slide. The coin is removed by inserting a finger upwardly through the finger opening 13 in the guide frame.

In Figure 8 an important modified form of 70 means for laterally ejecting a magnetic coin is shown, the main slide parts being shown and numbered the same as in the other views. However, in this modification the pins 30 and 49 are 75 eliminated and a spring pressed, guided hook

member is substituted therefor, such hook member serving as a positively acting striker which engages and positively forces the magnetic coin laterally out of the slide. As shown in Figure 8 a post 51 is carried on the top side of the 5 slide 22 adjacent its rear or inner end, said post pivotally carrying a forwardly extending member 52 having a hooked inwardly extending end 53, as shown. The member 52 is normally pressed into the full line position shown by a 10 spring 54, said hook 53 then lying in the space between the cam edge 48 and the forward edge of the plate 42, said plate 42 having a rounded guide corner 55 in this form of the invention. The edge of the guide frame is cut away at 15 15 to provide a passage for movement of the hook 53 in and out in relation to the slide. A guide plate 57 is welded to the adjacent side of the frame 12.

In use a magnetic coin is moved inwardly by 20 the slide until the magnet 44 picks it up. In the meanwhile such inward stroke of the slide 22 carries the hooked element 52 with it causing the hook part 53 to be forced laterally out of the slide, as it guides over the rounded corner 55. The end 25 of portion 53 then rides over the guide 57 as shown in the dotted line position of Figure 8. The empty coin pocket next receives the plungers 41 to lock the slide against further movement. When the slide is released by the operator a 30 spring such as 25, not shown, pulls the slide back, and at the same time, as the member 52 is pressed by spring 54 it is guided back until the hooked end is pressed forcibly through the passage 56 where it strikes, hammer fashion, against the trapped 35 coin and positively ejects the same from the magnet and slide in an obvious manner.

From this detailed description it will now be seen that an improved coin slide or chute has been provided which achieves the desirable objects 40 heretofore recited.

It is the intention to cover herein all such changes and modifications of the preferred form selected for this disclosure, which do not in material respects depart from the spirit and scope of 45 the invention.

What is claimed is:

1. In a device of the character described, the combination of an elongated slide having a coin receiving aperture, a guide frame for the slide 50 adapted to permit a full predetermined length of stroke when the slide aperture contains a coin, a magnet carried by the frame, said magnet being operative to take and hold a magnetic coin out of the aperture, lock means to prevent completion of the stroke under such circumstances, a spring to return the slide to its initial starting position, a plate having a cam edge carried by the frame, and a pin carried by the slide along its longitudinal median line, a second pin carried by the slide 55 in offset relation to the first pin, said pins acting as the slide returns to remove the coin from the magnet and cooperate with the cam edge to eject the coin from the slide.

2. In a device of the character described, the combination of an elongated reciprocating slide having a coin receiving aperture, a guide frame for the slide adapted to permit a full predetermined length of stroke for the slide when the latter contains a non-magnetic coin, a magnet 65 carried by the frame above the slide, said magnet acting to pick up and hold a magnetic coin advanced by the slide above the slide, a cam plate carried by the frame above the same and forwardly of the magnet, spring pressed means car- 70 75

ried by the frame to engage in the empty coin aperture and prevent completion of the stroke when the magnet has picked up the coin, and spaced members on the slide intermediately of its ends to remove the coin from the magnet and force it against the cam edge as the slide is returned to initial position, a spring to return the slide, said spaced members and cam cooperating to eject the coin laterally out of the slide, said cam plate having a passage therein to accommodate one of the spaced members as the slide reciprocates.

3. In a device of the character described, the combination of an elongated slide having a coin receiving aperture, a guide frame for the slide adapted to permit a full predetermined length of stroke for the slide when the latter contains a non-magnetic coin, a magnet carried by the frame above the slide, said magnet acting to pick up and hold a magnetic coin advanced by the slide above the slide, a cam plate carried by the frame above the same and forwardly of the magnet, a spring pressed plunger carried below the frame and magnet to engage in the empty coin aperture and prevent completion of the stroke when the magnet has picked up the coin, and a pair of spaced pins on the top side of the slide to remove the coin from the magnet and wedge it against the cam edge as the slide is returned to initial position, a spring to return the slide, said pins and cam cooperating to eject the coin laterally out of the slide.

4. In a device of the character described, the combination of an elongated slide adapted to move a coin, a guide frame for the slide adapted to permit a full predetermined stroke when the slide moves a coin, a magnet carried by the frame adjacent the slide, said magnet being operative to take and hold a magnetic coin away from the slide, lock means to prevent completion of the stroke of the slide under such circumstances, said slide adapted to be drawn back to its initial starting position, a plate having a cam edge carried by the frame, a pin carried by the slide substantially on the longitudinal median line thereof,

and another pin carried by the slide in offset relation to the first pin, said pins acting as the slide is drawn back to remove the magnetic coin from the magnet and cooperate with the cam edge to eject the coin from the slide.

5. In a device of the character described, the combination of an elongated, reciprocatory slide adapted to move a coin, a guide frame for the slide adapted to permit a full predetermined length of stroke for the slide when it moves a non-magnetic coin, a magnet carried by the frame above the slide, said magnet acting to pick up and hold a magnetic coin advanced by the slide above the slide, a cam edged plate carried on the frame forwardly of the magnet, means to prevent completion of the stroke when the magnet picks up the coin, a plurality of spaced pins on the slide intermediately of its ends to remove the coin from the magnet and with the cam edge to eject the said coin from the slide on its return stroke, said cam edged plate having a groove to accommodate one of the pins when the slide reciprocates under said plate.

6. In a device of the character described, the combination of an elongated, reciprocatory slide adapted to move a coin, a guide frame for the slide adapted to permit a full predetermined length of stroke for the slide when it moves a non-magnetic coin, a magnet carried by the frame above the slide, said magnet acting to pick up and hold a magnetic coin advanced by the slide above the slide, a cam edged plate carried on the frame forwardly of the magnet, a spring pressed dog reciprocable through the cam edged plate to lock the slide against movement if no coin is moved by the slide, a plurality of spaced upstanding elements on the slide intermediately of its ends to remove a magnetic coin which is held by the magnet and with the cam edge to eject the said coin from the slide on its return stroke, said cam edged plate having a groove to accommodate one of the upstanding elements when the slide reciprocates past the plate.

HERBERT G. BREITENSTEIN. 45
